UNITED STATES PATENT OFFICE

LEWIS J. CLAPP, OF CLAREMONT, NEW HAMPSHIRE, ASSIGNOR TO SULLIVAN MACHINERY COMPANY, A CORPORATION OF MASSACHUSETTS

COMPRESSOR

Application filed December 15, 1928. Serial No. 326,349.

My invention relates to cooling systems for thermo-dynamic machines, and more particularly to control means for a liquid cooling system for compressors.

5 The water jackets for the cylinders and valve housings of compressors are frequently connected to a supply of cooling water which is limited or which has to be paid for at a certain price per cubic foot where the liquid 10 cooling system is connected to some city water main. It is accordingly highly essential that the water circulation be shut off at all times when the compressor is not in actual operation. Of course this may be done by a 15 manually controlled valve in the liquid circulating line if the operator is careful to shut this valve off when the compressor is shut down and open the same again when the compressor is started up. However, the operator 20 may forget to close the valve at night when the compressor is shut down or open the same in the morning whereby there would either be an excess of water used or the compressor might be overheated if the operator 25 forgets to turn on the valve. Moreover, it is advantageous to interrupt the cooling water supply when the compressor is running unloaded, and this would demand too much attention. A major object of my invention is 30 therefore to provide improved automatic means for cutting off the flow of circulating liquid in a cooling system when the compressor is not running and for permitting flow during operation of the compressor. 35 From a general aspect it is an object of my invention to provide improved control means for cooling systems of all thermodynamic machines. Another object of my invention is to provide a control valve for a liquid 40 cooling system of improved design having automatic means for holding the valve closed when the compressor is not in operation and means responsive to discharge pressure for normally holding the valve open during operation of the compressor. A still further object of the invention is to provide a valve in a liquid circulating system for a compressor with a control means for automatically opening the valve when the compressor is started 45 up and closing the same when the compressor

is shut down, and superior controlling means for closing the valve when the compressor is running unloaded. Other objects and advantages of my invention will hereinafter more fully appear.

55

In a preferred embodiment my invention comprises means for controlling the flow of cooling liquid through the jacketing of a compressor, such means having, for effecting its operation to cause flow of the cooling fluid, provision which depends for its effectiveness upon a function of the operation of the compressor. In a preferred form a controlling valve is moved to open position by an element to which pressure is applied by fluid compressed by the compressor. Operation of such an element may obviously be controlled, within the purview of my invention, by other means whose effectiveness is a function of the running of the compressor, as by an element whose position is controlled by a speed responsive device which is operated with the compressor itself. Preferably the element is yieldingly controlled so that a superior pressure may control the position of the flow controlling means, and in the preferred embodiment of the invention such a superior pressure is automatically exerted by means under control of the compressor unloading system so that the cooling water flow is interrupted when the compressor is unloaded.

75

80 In the accompanying drawings I have shown for purposes of illustration one form which my invention may assume in practice.

85

In these drawings,—

Fig. 1 is a diagrammatic view in elevation of the essential elements of a compressor system with which the illustrative embodiment of my improved cooling water control mechanism is associated.

90

Fig. 2 is a central sectional view through the illustrative embodiment of my improved cooling liquid controlling mechanism.

95

In Fig. 1 there is shown a simple form of single cylinder compressor 1 supported on a base 2 and arranged to discharge into a receiver 3 through a discharge pipe 4. It will be understood that my invention may be applied to any compressor either portable or

100

stationary, single or multi-stage, and in its broadest aspects may be applied to cooling systems for internal combustion engines.

As is common in actual practice, the compressor illustrated in Fig. 1 is equipped with unloading mechanism 5 of a type adapted to hold the inlet valves at opposite ends of the cylinder open by fluid pressure supplied through pipes 6 and 7 which are connected 10 to an unloader pilot valve 8 by a common pipe 9. This pilot valve may be of any of the well known types which will operate automatically to supply pressure fluid to the unloaders upon a predetermined high receiver 15 tank pressure and to vent the unloaders for loading the compressor on a predetermined low pressure in the receiver. The pilot valve is shown connected to the receiver by a pipe 10. The cylinder and valve mechanisms of 20 the compressor are provided with the usual water jackets which have not been illustrated since their specific construction per se is not a part of my present invention. Cooling liquid is supplied to the water jackets of the 25 compressor from an inlet connection 11 through valve mechanism generally designated 12 and a pipe 13 leading from the valve and connected to the compressor at 14.

The illustrative embodiment of my improved valve mechanism comprises a valve casing 15 in which is mounted a double-seat valve element 16 which is normally held in closed position by a coil spring 17 when the compressor is not in operation. For the purpose of automatically opening the liquid control valve upon starting up of the compressor, pressure responsive mechanism is connected to the receiver by a pipe 18 and this pressure responsive device comprises a cylinder 19 30 formed integrally with the valve casing 15 and a piston 20 mounted in said cylinder, one side of the piston being supplied with pressure from line 18 and the other side vented to atmosphere by means of ports 21. The 35 piston has an upwardly projecting stem 22 connected thereto which engages the valve element 16 and lifts the same, unless prevented by superior pressure, when the piston 20 is moved upwardly by pressure.

At the upper end of the valve casing is a second cylinder 23 also herein formed integral with the valve casing 15, this cylinder being connected with the pilot valve 8 by means of a pipe 24 so as to be supplied with pressure fluid during unloading of the compressor. A piston 25 is reciprocably mounted in cylinder 23 and has a cylindrical recess 26 in which is received the spring 17. When pressure is supplied to the cylinder 23 from pilot valve 8, piston 25 is forced downwardly, thereby compressing spring 17 and engaging valve 16 and closing the same notwithstanding the fact that piston 20 is tending to urge the valve upwardly since the cylinder 23 and

piston 25 are of much larger cross section than piston 20 and cylinder 19.

The operation of the illustrative embodiment of my improved cooling liquid control mechanism will now be readily understood. 70 Pipe 11 is simply connected to a source of liquid under pressure and no further attention need be given the cooling system by the operator. The valve will normally be closed under the action of spring 17 until the compressor is started. When the compressor is started, sufficient pressure is very quickly built up in the receiver to cause the piston 20 to actuate the water control valve to open position. This permits cooling liquid to flow 80 through the water jacket of the compressor at all times during normal effective operation of the compressor. However, when the compressor is automatically unloaded under the action of the pilot valve 8, the compressor 85 piston simply reciprocates in its cylinder without during any work and there is no need for circulation of cooling water. At this time pressure fluid is also supplied to cylinder 23 and the valve is again actuated to 90 closed position, thereby cutting off the cooling liquid during unloading of the compressor. When the compressor is again loaded, cylinder 23 will be vented to atmosphere and pressure acting on piston 20 will 95 open the cooling water control valve. Now when the compressor is shut down for any length of time, the compressed fluid remaining in the receiver tank will either leak out or be purposely vented to atmosphere. This 100 will relieve the pressure on piston 20 and the valve will be closed by spring 17.

It will therefore be seen that my improved cooling water control valve mechanism automatically cuts off the supply of cooling 105 water when the compressor is shut down and is automatically opened again when the compressor is started up. This insures against waste of cooling water or damage to the machine through failure of the operator to attend to the usual manual control valve in the cooling water supply line. 110

While I have in this application specifically described one form which the invention may assume in practice, it will be understood 115 that this form of the same is shown for purposes of illustration and that the invention may be modified and embodied in various other forms without departing from its spirit or the scope of the appended claims.

What I claim as new and desire to secure by Letters Patent is:

1. In combination, a compressor, a receiver, an unloader for said compressor, a pilot valve responsive to receiver pressure for controlling said unloader, a fluid cooling system for said compressor, a valve for controlling flow of fluid in said cooling system, valve controlling means operative as receiver pressure builds up to open said cooling fluid flow con- 120 125 130

- trolling valve and, during normal loaded operation of said compressor, to hold said cooling fluid flow controlling valve in open position, and superior valve controlling means 5 controlled by said pilot valve for automatically effecting closure of said cooling fluid flow controlling valve when the compressor is unloaded.
2. In combination with a compressor having an unloading mechanism, a receiver, a pilot valve connected to said receiver for controlling said unloading mechanism, a liquid cooling system for said compressor, a valve controlling flow of liquid in said system, a spring for holding said valve closed when said compressor is not in operation, means including a cylinder and a piston therein continuously subjected to pressure in said receiver for holding said valve open 15 during loaded operation of said compressor, and an opposed cylinder and piston of larger cross section than said first cylinder and piston connected to said pilot valve for closing said liquid control valve during unloading 20 of the compressor.
3. In combination, a machine, a liquid cooling system therefor, a valve for controlling flow of liquid in said system, and means for controlling said valve including means 25 for respectively moving the valve to closed and open positions by fluid pressure and a spring arranged to hold the valve closed when said fluid pressure means are both inactive.
4. In combination, a compressor having an unloading mechanism, a liquid cooling system for said compressor, a valve for controlling flow of liquid in said cooling system, a receiver, means for opening said valve operative only after receiver pressure reaches 30 a predetermined value, a pilot valve connected to said receiver and to said unloading mechanism, means for moving said liquid valve to closed position by fluid pressure which is controlled by said pilot valve, 35 whereby upon a predetermined maximum receiver pressure said pilot valve effects simultaneously unloading of said compressor and closure of said liquid valve.
5. In combination, a compressor having an unloading mechanism, a liquid cooling system therefor, a valve for controlling flow of liquid in said cooling system, a receiver, means for moving said valve to open position with fluid pressure supplied directly from 40 said receiver, fluid pressure means for moving said valve to closed position, a pilot valve connected to said receiver, and fluid pressure connections from said pilot valve to said unloading mechanism and to said fluid pressure 45 means for moving the liquid control valve to its closed position, whereby when receiver pressure reaches a predetermined maximum said pilot valve simultaneously unloads said compressor and closes said liquid valve.
6. In combination, a compressor, a fluid
- cooling system therefor, and means for controlling flow of cooling fluid in said system including a valve constantly biased towards closed position, means controlled by compressor discharge line pressure for opening said valve when said pressure exceeds a predetermined value, and means automatically operative when said compressor discharge line pressure exceeds a desired maximum to effect closure of said valve while said valve opening means continues to exert its valve opening force.
7. In combination, a compressor, a fluid cooling system therefor, and means for controlling flow of cooling fluid in said system including a valve constantly biased towards closed position, means responsive to compressor discharge pressure for opening said valve when compressor discharge line pressure exceeds a predetermined value, and means automatically operative when said discharge line pressure exceeds a desired maximum to effect closure of said valve while said valve opening means remains subjected to discharge line pressure.
8. In combination, a machine, a liquid cooling system therefor, a valve for controlling flow of liquid in said system, and means for controlling said valve including an element for moving the valve to open position by fluid pressure and a superior fluid responsive means for forcing said valve to closed position.
9. In combination, a receiver, a compressor discharging to said receiver and having an unloading mechanism, a liquid cooling system for said compressor, a valve for controlling flow of liquid in said cooling system, yielding means constantly acting to press said valve towards closed position, means for moving said valve to open position by fluid pressure supplied from said receiver, a pilot valve connected to said receiver and to said unloading mechanism, and a fluid pressure responsive means also connected to said pilot valve for closing said liquid controlling valve when pressure in said receiver reaches the value at which unloading takes place.
- In testimony whereof I affix my signature.
- LEWIS J. CLAPP.
